UNITED STATES PATENT OFFICE.

PETER WHITE, OF ST. LOUIS, MISSOURI.

VALVE.

SPECIFICATION forming part of Letters Patent No. 241,174, dated May 10, 1881.

Application filed September 14, 1880. (No model.)

To all whom it may concern:

Be it known that I, PETER WHITE, of St. Louis, Missouri, have made a new and useful Improvement in Valves, of which the following is a full, clear, and exact description, reference being had to the annexed drawings, making part of this specification, in which—

Figure 1 is a vertical section taken through the valve, the valve being closed; Fig. 2, a vertical section taken through the valve, the section being taken at right angles to that of Fig. 1; Fig. 3, a section of the valve, showing the valve open; Fig. 4, a detail, being a sectional view of the lower end of the stem of the valve; Fig. 5, a view of the seat that the valve-stem bears upon when the valve is closed; Fig. 6, a section taken on the line $x' x'$ of Fig. 2; and Fig. 7, a sectional view, showing an application of a portion of the improvement to a bib-cock.

The same letters denote the same parts.

A prominent feature of the present invention is a valve-stem having two cup-leathers, opening from each other and working in a cylindrical chamber, that part of the valve-stem which is between the leathers being, when the valve is closed, opposite the inlet into the valve-chamber, and the discharge from said chamber being at a different level from the inlet.

The improvement also relates to the construction of the lower end of the valve-stem, or the means for assisting the upward movement of the valve, and to the means for regulating the flow of water to the valve.

Referring to the drawings, F represents the improved valve. The inlet to the valve is at G. The chamber f, in which the valve F works, is cylindrical. The valve is constructed as follows: The stem f' is furnished with two cup-leathers, H and H'. When the valve is closed, as in Figs. 1, 2, the lower end of the stem rests upon a seat, I, and the leathers H H' are respectively above and beneath the inlet G. The discharge from the valve-chamber is at J, below or beyond the terminus of the movement of the leather H'. The water may flow to the inlet G through the tube G', passing thence into a side pipe or channel, g, and thence through the inlet G. The tube G' and pipe g may, however, take the form shown at G², Fig. 7, as it is immaterial, so far as the working of the valve F is concerned, from what source the water is supplied to the inlet G. To regulate the flow through the tube G' a thimble, K, is

used. By screwing it into the tube G' the opening into the pipe g is diminished. This is desirable when there is a heavy pressure in the main. The seat I is of suitable material, and is mounted on a plug, I', that can be screwed in and out in the bearing i, and thus adjusted as desired. Arranged as shown in Figs. 1, 2, no water can pass the valve, the pressure operating to expand the leathers H H' both above and below the inlet G. As soon, however, as the valve begins to lift and leave the seat I water in small quantity flows through a perforation (shown at f², Figs. 3, 4) into the space J' and discharge J. By reason of the cup-leathers H H', arranged and operating as described, the operation of the valve F is rendered easy, but allowing the water to at once flow through the perforation f², as described, the ascent of the valve immediately at the initiation of the movement is facilitated.

The stem of the valve F may be provided with a weight, W, to render the valve more sensitive in its action when it is connected with other mechanism, as that of a water-closet.

The leathers H H' operate to pack the valve F perfectly, obviating the need of any other packing at the top of the valve-chamber. They also serve to balance the valve and render it easy in its action.

I claim—

1. The valve F, working in a cylindrical chamber, f, and provided with the cup-leathers H H', and having the inlet G and outlet J, the inner sides of said leathers being toward each other, and that part of the valve-stem which is between the leathers being, when the valve is closed, opposite said inlet, and when the valve is opened above said inlet, enabling the water to pass below the lower leather to the outlet, substantially as described.

2. The valve F, having the stem perforated at f², seat I, inlet G, and outlet J', combined substantially as described.

3. In combination with the adjustable seat I, the perforated stem f', substantially as described.

4. The combination of the tube G', pipe g, and adjustable thimble K, substantially as described.

Witness my hand.

PETER WHITE.
